DESIGN FOR A COMBINATION HOLDER FOR NAPKINS AND CONDIMENT SETS

Robert E. Dye, Los Angeles, Calif.

Application May 15, 1945, Serial No. 119,554

Term of patent 7 years

(Cl. D44—24)

To all whom it may concern:

Be it known that I, Robert E. Dye, a citizen of the United States of America and a resident of the city of Los Angeles, in the county of Los Angeles and State of California, have invented a new, original, and ornamental Design for a Combination Holder for Napkins and Condiment Sets, of which the following is a specification, reference being had to the accompanying drawing, forming part thereof.

In the drawing:

I claim:

The ornamental design for a combination holder for napkins and condiment sets, substantially as shown.

ROBERT E. DYE.
